APPARATUS FOR RECORDING AND/OR REPRODUCING SOUND

Filed Aug. 26, 1929

UNITED STATES PATENT OFFICE

1,925,608

APPARATUS FOR RECORDING AND/OR
REPRODUCING SOUNDHenry Joseph Round, Muswell Hill, London,
England, assignor to Marconi's Wireless Tele-
graph Company, Limited, London, EnglandApplication August 26, 1929, Serial No. 388,396,
and in Great Britain September 7, 1928

3 Claims. (Cl. 179—100.3)

In apparatus for broadcasting, making gramophone records, talking film records or the like, difficulty has been experienced owing to the fact that the differences in the volume or strength of the sounds to be broadcast or recorded are very large.

If, for example, there is being made on a gramophone disc a record of music, part of which is played by a large orchestra and part by solo instruments, or pianissimo passages by the orchestra, the solo or pianissimo passages are below the "ground noise" of the reproducing disc, if the loudest passages are properly recorded.

In order to overcome this disadvantage, various forms of control have been employed, partially to decrease the differences in the volume of sound which is broadcast or the strength of cutting of the gramophone or like record. In some cases a musician reads the score and adjusts the volume of sound, increasing the volume of the soft passages and decreasing the volume of the loud passages. In other cases, the variations in the cut on the record, corresponding to the volume of sound, have been kept automatically within limits.

This is an advantage to the user of the record or the broadcast receiver, in which the output apparatus is of very limited power, but in cases where the output system is capable of producing a strength approximately equal to the orchestra, it is obviously a disadvantage that such a repression of the variations in the volume of the music should take place.

According to the present invention I provide means for making a record of sounds so that the variations in amplitude in said record lie within limits which are narrower than the limits which would be obtained if sounds of all amplitudes were proportionately recorded (that is to say sounds of strong amplitude are recorded at less amplification than the amplification of sounds of weak amplitude) and I make a record of the degree of control employed. When the sounds are reproduced, the control record is utilized inversely to negative the control exercised on the recorded differences between the volume of the loud and soft sounds, whereby the correct variations are reproduced.

In the case of talking films or the like, the control record and the sound record may be recorded side by side, the former being utilized when "playing off" to restore the reproduced sounds to correspond in intensities to the sounds originally recorded.

It is already known in sound recording to make

two records of the sound, (a) a record of the sound reduced to an arbitrary and artificial standard intensity, i. e. a record of constant amplitude, and (b) a record of the intensity of the sound. In the production of the (a) record the instantaneous amplitudes of the recorded sound variations are controlled by the same energy which produces the (b) record so that as a result two sound records are produced, in one of which the amplitude is constant (though it may be varied from time to time), the other record being a record of the variations necessary to reduce the varying intensity sounds to a constant amplitude. In "playing off" from records so made the record of control is utilized to insert an inverse correction in an amplifier or the like in the reproducing apparatus so that sound varying in intensity in the same way as the original sound which was recorded is reproduced.

The present invention is distinguished from this known method of recording in that the sound recorded is not reduced to an arbitrary or artificial standard intensity, i. e. it is not brought to a constant amplitude, the present invention consisting in recording the sound so that the variations of amplitude in the record lie within limits which are narrower than they would be if sounds of all intensities were recorded proportionately.

Methods of effecting limitation for various purposes have been suggested, and it has been proposed to employ the actual strengthening of a sound, or a derivative thereof, to actuate a controlling or limiting system. For example, the output from a microphone receiving sounds may be rectified and partially smoothed, so that only the larger slow variations of amplitude are left, these variations being utilized to actuate a suitable device adapted to alter the sensitivity or magnification of an amplifier associated with the microphone.

With arrangements of this kind, the control will be a little late in action, and over-modulation, due to large intensity sounds, may occur before the control comes into action. To avoid this, it is desirable to provide means whereby the control is brought into action a little before the sound or derivatives thereof, which are to be controlled in intensity, reach the point at which said control is effected.

To this end a delay circuit or equivalent device may be inserted in the "sound" channel before the point at which control is to be effected, whereby the "sound" (i. e. sound or derivatives thereof) is prevented from reaching said point before the control currents have actuated the control.

In some cases, for example, in so-called talking pictures it may be preferred to make two or more sound records of a sound, the said records corresponding each to the output of one of a plurality of stereophonically arranged microphones or the like, i. e. microphones arranged at different positions and "listening" to the same sound source. In such cases it will generally be found that only one control record (i. e. record of the degree of control employed in recording the sounds) is necessary since the control for all the stereophonically recorded sound records will ordinarily be the same, but sometimes two or even more control records will be desirable.

15 In arrangements in which separate sound films are required for "projection" at the same time, e. g. a sound film of a man singing and a separate film of a band playing, said films being recorded separately, two control records may be necessary.

20 The invention is illustrated in the accompanying schematic drawing.

Referring to Figure 1, which illustrates one way of carrying out the invention as applied, for example, to a talking film, M is a microphone whose output is fed to an amplifier A which in turn actuates means, LS, for making a sound trace SR upon a film F. In this arrangement, control is effected by hand by operating a handle H which controls the amplification of the amplifier A. The handle H also operates a variable resistance V in series with a battery B and lamp L2, the light from which is focused by a lens S2 upon the film F so as to give a second trace CR which, as will be seen, is a record of the degree of control employed.

35 In the modification shown in Figure 2, the control and recording of the degree of control is effected automatically. In the arrangement illustrated, the amplification of the sound amplifier A is controlled by impressing a varying bias potential upon the grid of an auxiliary valve X, associated with the amplifier A in some such way as is illustrated in Figure 2, in which the valve X forms with the resistance R an alternating current potentiometer controlled in accordance with the output from the microphone M. This control is effected by means of a separate amplifier B, which incorporates amplifier valves, a rectifier, and some form of smoothing circuit adapted to eliminate all but slow variations. As will be seen, the amplifier B has its input side fed from the microphone M, while its rectified and smoothed output is utilized to apply controlling grid bias to the valve X. In this way the amplification of the amplifier A is directly controlled by the strength of sound. The control box B containing the rectifier also feeds energy to the lamp L2 which makes a record of control, as in Figure 1.

60 Figure 3 shows a further modification, differing from that shown in Figure 2 only in that a delay device DC is interposed between the microphone M and the amplifier A. This delay device may comprise a circuit consisting of an artificial, and as nearly as possible distortionless, line having a time delay of, say one tenth or one fifth of a sound such as series impedances DCL and parallel capacities DCC interposed between the microphone M and the amplifier A. Or the delay device DC may comprise an arrangement in which the sound is delayed by its effect being caused to pass through a mechanical line of solid liquid or gas, the delay in this case being occasioned by the length of time taken by the sound vibrations to traverse the line or the delay device

DC may be constituted by a telephone, the time delay being in this case equal to the time taken by the magnetized wire or the like to pass from the point at which the magnetism of a moving endless wire or the like is varied by sound derivates to the point at which said variations are transformed back into electrical variations. It will be seen that with such arrangements in accordance with this invention the control will be effected a little early, and in consequence the desired limitation will be satisfactorily obtained.

80 Preferably the control is made slightly sluggish in recovery, so as to overlap the sound slightly at the end of the time necessary for said control.

85 Figure 4 illustrates an arrangement for playing off from a record made, for example, by the apparatus shown in Figure 2. In this figure L3 is a source of light which is focused by a lens system S3 upon the trace SR. Light modulated in accordance with said trace falls upon a photoelectric cell P1 whose output is amplified by means of an amplifier A' feeding a loud speaker LS to reproduce the sound. A sound lamp lens and photo-electric cell system L4 S4 P2 "pick up" from the control trace CR, the output from the cell P2 being fed to an amplifier CA which serves to control the amplification of the amplifier A' in a manner analogous to that in which the control box B controls the amplifier A (Figure 2), so that in "playing off" the control originally exercised is negated and the variations in the volume of sound are correctly reproduced.

90 The time delay means illustrated in Figs. 2 and 3 may be readily applied to the circuit arrangement shown in Fig. 1. The time delay feature of my invention is applicable to all of the embodiments illustrated.

95 Where two or more sound records are made of a single sound by means of stereophonically arranged microphones, as hereinbefore described, the record or records of control may be made by the side of the sound records on a single film, if desired. The said sound records may be constituted in any well known way—for example, by photographically recording the movement of a spot or spots of light—and are made by recording the electric variations (or variations corresponding thereto) obtained from a pair of stereophonically arranged microphones which are subjected to the influence of the sound to be recorded, one record corresponding to the output from one microphone and the other to that from the other.

100 In reproducing (for talking pictures) from stereophonic films as above described, the two records are employed each for controlling one of two loud speaking devices arranged one on either side of the screen on which the pictures are projected.

105 In some cases the film or films may comprise three or even four sound records, so as to represent up and down, as well as sideways motion, to an audience, the said records being utilized to operate each one of a plurality of appropriately arranged loud speakers.

110 It will be understood that although the invention has for the most part been described with reference to sound records made upon films, it is equally applicable to other kinds of sound records—for example, gramophone records.

115 What I claim is:—

120 1. A sound recording system comprising a film adapted to receive a pair of light records, a pair

- of recording devices adjacent said film for impressing variable records thereon, a microphone circuit, a pair of amplifying channels having their input circuits connected with said microphone circuit, the output circuit of one of said channels being connected with one of said recording devices and the output circuit of the other of said channels being connected with the other of said recording devices, one of said channels 5 including a multiple stage amplifier having coupling means interconnecting said stages, the other of said channels including a rectifier and an electron tube amplifier, an auxiliary electron tube having its input circuit connected with the coupling means in said first mentioned amplifier and its output circuit connected with said last mentioned electron tube amplifier for variably controlling the operating characteristics thereof and correspondingly controlling the intensity of the 10 associated recording device for impressing a variable control record on said film in addition to the recording of a variable sound record under control of the recording device connected with the output of said first mentioned multiple stage 15 amplifier.
2. A sound recording system comprising a film adapted to receive a pair of light records, a pair of recording devices adjacent said film for impressing variable records thereon, a microphone circuit, a pair of amplifying channels having their input circuits connected with said microphone circuit, the output circuit of one of said channels being connected with one of said recording devices and the output circuit of the other of said channels being connected with the other of said recording devices, one of said channels 20 including a multiple stage amplifier having coupling means interconnecting said stages, the other of said channels including a rectifier and an electron tube amplifier, an auxiliary electron tube having its input circuit connected with the coupling means in said first mentioned amplifier and its output circuit connected with said last- 25 mentioned electron tube amplifier for variably controlling the operating characteristics thereof and correspondingly controlling the intensity of the associated recording device for impressing a variable control record on said film in addition to the recording of the variable sound record under control of the recording device connected with the output of said first mentioned multiple stage 30 amplifier, and means comprising a multiplicity of series connected impedances and a plurality of shunt connected impedances disposed between said microphone circuit and said first mentioned amplifier for delaying the operation of the recording device in the output of said first mentioned amplifier with respect to the operation of the recording device in the output of said second mentioned amplifier for displacing the control record from the sound record on the film. 35
